UNITED STATES PATENT OFFICE.

WILLIAM WAINWRIGHT, OF SAN FRANCISCO, CALIFORNIA.

VAPOR-BURNER.

SPECIFICATION forming part of Letters Patent No. 357,798, dated February 15, 1887.

Application filed February 3, 1886. Serial No. 190,740. (No model.)

To all whom it may concern:

Be it known that I, WILLIAM WAINWRIGHT, of the city and county of San Francisco, State of California, have invented an Improvement 5 in Vapor-Burners; and I hereby declare the following to be a full, clear, and exact description of the same.

My invention relates to the class of burners which are used for burning the vapor arising 10 from the lighter or more volatile oils, such as gasoline, naphtha, &c.; and my invention consists in the construction and combination of devices, all of which I shall hereinafter fully describe by reference to the accompanying 15 drawings, in which—

Figure 1 is a view showing the pedestal of a lamp in elevation and its reservoir, wick-tube, and burner in vertical section. Fig. 2 is a vertical section showing the burner-valve. 20 Fig. 3 is a modification of same. Fig. 4 is a vertical section showing the flanges attached to a sleeve fitted on the burner-tube.

The object of my invention will appear in the course of the following description. 25 A is any form of lamp-stand, having an oil-reservoir, B, with the usual screw, b, in its top.

C is the wick-tube having a threaded flanged base, whereby it is screwed into the oil-reservoir. Upon the lower portion of this tube is formed or secured in any suitable manner a spiral thread or screw, D, upon which is seated a threaded collar or nut, d, provided with ears d', from which two small rods, E, extend upwardly, and are united at their tops to a plate, F. 30

G is an annular socketed piece or seat internally threaded and having a tubular stem, g', said piece and stem being fitted on the tube C. The plate F is seated loosely in a groove, g'', in said stem. 40

H is the wick, which extends from the oil-reservoir through the wick-tube C.

I is the burner-tube, consisting of a short pipe fitting over the top of the wick-tube C and having an externally-threaded flange, i, on its base, which is screwed into the socketed piece G, packing g being placed within said socketed piece so as to make a vapor-tight joint. 45

The operation of the mechanism as far as described is as follows: By turning the nut d upon the screw D so that it rises, the plate F

above also rises, forcing upwardly the socketed piece G, and thus causing the burner-tube I to move up on the wick-tube C. By turning 55 the nut d down again the plate F draws the socketed piece and the burner down. The object of this adjustment is to regulate the amount of flame desired, which is accomplished by increasing or decreasing the distance between 60 the point of ignition and the top of the wick. Thus when the burner is moved down a greater heat is thereby obtained, which generates more vapor and causes an increase in the body of the flame, and when the burner-tube is raised 65 there is less heat and consequently less vapor generated, and the size of the flame is thereby reduced.

J is a heating and directing flange, which is secured on the top of the burner. This flange 70 has a fan-shape in outline, and is concave on its surface next to the flame. It may be secured directly to the top of the burner, as shown in Fig. 3; or it may be secured to a small sleeve, j, which is adapted to fit over the 75 top of the burner-tube, as is shown in Fig. 4.

The flange J is hinged to the top of the burner in any suitable manner, as is shown by the horizontally-arranged pintle j', Fig. 1, passing through suitable sockets on the top of the 80 burner and the base of the flange. From the flange extends downwardly an arm, j'', through which passes a screw, j', which bears against the side of the burner. By turning this screw in such a way as to withdraw the arm from 85 the burner it will be seen that the flange is thrown forwardly over the top of the burner, while by reversing the movement of the screw it is drawn backwardly. This hinge may be connected directly with the top of the burner, 90 as shown in Fig. 1, or it may be hinged to the sleeve j, which is fitted over the top of the burner, as is shown in Fig. 4. The object of the flange is to increase the vapor generating heat, and also to spread the flame to a fan 95 shape, its construction being adapted for this purpose.

The object of hinging the flange so as to render it adjustable is as follows: In the first place, it regulates the quality of the flame. 100 When forced over the burner, the vapor-jets, coming in contact with the flange more quickly, have less opportunity to gather oxygen from the air, and the flame is therefore darker and

emits a greater quantity of smoke, showing an imperfect combustion. When the flange is moved back, the points at which the jets strike it being further removed from the ports through which the vapor escapes, there is more oxygen gathered and the flame burns whiter and with less smoke. By the movement of the flange I can therefore regulate the quality of the light. In the next place, the movement of the flange enables the operator to get at the ports in the valve and to clear them out when they become stopped up from any cause. The flange J may be used alone, as is shown in Fig. 4, or it may be used in connection with a supplementary flange, K, such as is shown in Figs. 1, 4. This flange may be straight or curved, and is preferably made smaller than the flange J. It may be hinged as said flange is, or it may be fixed in position. It forms, with the flange J, a large open-ended slot across the top of the burner, and assists in the heating and spreading effect.

The burner may be made with a top having minute perforations made directly through it, as shown in Fig. 1, and these perforations are preferably made obliquely and in such a way that the jets of vapor emitted from each will cross those from the other, as in an ordinary metal gas-burner.

Across the top of the burner-tube is made a socket, M, having a plugged end, an open end, and an aperture, m, in its middle. The burner-tube communicates with the socket by a small passage, m', near the plugged end. Within this socket is fitted the spigot-valve N, having an open inner end, which communicates with the passage m', and having minute perforations n in its body, which are just under the aperture m in the socket. These perforations may be made in any number and on different sides—as, for example, I could have one on one side, two on another, three on another, and so on—whereby upon turning said valve the different sets of ports may be brought into communication with the aperture m in the socket and a greater or less light obtained. The spigot-valve projects from one end of its seat, and may be turned by a suitable key. The valve and its seat may be arranged horizontally, as shown in Fig. 2, or at an angle, as shown in Fig. 3.

O is a shade-bracket consisting of wire arms secured in a collar, o, which is fitted in the groove g² of the stem g' of piece G above the plate F, so that said collar has a firm support and moves up and down with the burner. In case I wish to provide for the removal of the shade-bracket, I screw the downwardly-extending stem g' of piece G into internally-threaded lock-nuts P, seated on the wick-tube C just above the threaded portion D thereon. By unscrewing the socketed piece G it can be taken off, whereby the shade-bracket may also be removed.

Having thus described my invention, what I claim as new, and desire to secure by Letters Patent, is—

1. The wick-tube C, having a spiral thread or screw, D, and the burner-tube I, resting upon the top of said wick-tube, in combination with a threaded exterior nut traversing the screw D, a plate, F, and the rods E, by which said plate is connected with the nut, whereby the burner is vertically adjusted, substantially as herein described. 70

2. The wick-tube C and the burner-tube I, fitted upon the wick-tube, in combination with the socketed piece G, seated on the wick-tube and receiving the base of the burner-tube, and a threaded nut for moving said socketed piece 80 longitudinally on the wick-tube, substantially as herein described. 75

3. The wick-tube C, having a threaded portion, and the burner-tube I, fitted upon the wick-tube, in combination with the socketed 85 piece G, having stem g', seated on the wick-tube and receiving the base of the burner-tube, a mechanism for adjusting said piece G and burner I, consisting of the threaded nut d, plate F, and rods E, connecting the nuts and 90 plate, substantially as herein described.

4. In a vapor-burner, the wick-tube C, having a spiral thread or screw, D, and the burner-tube I, fitted upon the top of the wick-tube and having an externally-threaded base, i, in 95 combination with the internally-threaded socketed piece G upon the wick-tube, receiving the base of the burner, said piece having a grooved stem, the nut d on the screw D, the rods E, connected with the nuts, and the plate 100 F on top of the rods, fitted on the grooved stem of the socketed piece G, whereby the burner is vertically adjusted, substantially as herein described.

5. In a vapor-burner, the wick-tube C, having a spiral thread or screw, D, and the burner-tube I, fitted upon the top of the wick-tube, in combination with the movable socketed piece G, in which the burner-tube is seated, said piece having a stem, g', the nut d on the screw 110 D, the plate F on the stem g', the connecting-rod E between said nut and plate, and the shade-bracket O, having a collar, o, fitted upon the stem g' between the plate and the socketed piece, substantially as herein described. 115

6. In a vapor-burner, the wick-tube C, having a screw, D, the burner-tube I, fitted upon its top, the socketed piece G, fitted upon the wick-tube and receiving the base of the burner-tube, said piece having a threaded stem, g', and the lock-nuts P, into which the stem screws, whereby it may be secured and removed, in combination with the nut d on the screw D, the plate F on the stem g', the connecting rods E between the nut and plate, and the shade-bracket O, having a collar, o, fitted upon the stem g' between the plate and the socketed piece, substantially as herein described. 125

7. The combination, with a vapor-burner, 130 of the flange J, hinged at the top of the burner and having a downwardly-extending arm, j², and the screw j³, passing through said arm and bearing against the burner, whereby the

flange may be adjusted forward and back, substantially as herein described.

8. The tube I, having a socket or valve-seat, M, on its top, closed at one end by a plug and open at the other and provided with an aperture, m, as described, said socket or seat communicating with the tube by a passage, m', near the plugged end, in combination with the spigot-valve N, fitting in said socket or seat, 5 its inner end communicating with the passage m' from the tube, said valve having minute ports n in its body communicating with the aperture m in the socket or seat, substantially as herein described.
- 15 9. In a vapor-burner, the valve seat or socket M on top of the burner-tube, in combination with open-ended spigot-valve N, fitting said seat and provided with perforations

n in its body, located in different portions and made in different numbers, whereby the light 20 may be increased or diminished by the turning of said valve, substantially as herein described.

10. The combination, with a vapor-burner having a tube, I, of the flange J, hinged at 25 one side to said tube, a smaller flange rigidly secured to the opposite side of the tube, and a means comprising a screw for adjusting the hinged flange, substantially as herein described.

In witness whereof I have hereunto set my hand.

WILLIAM WAINWRIGHT.
